UNITED STATES PATENT OFFICE.

SIMON W. WARDWELL, OF PROVIDENCE, RHODE ISLAND.

SUPPLY-CARRIER FOR BRAIDING-MACHINES.

1,072,800.

Specification of Letters Patent.

Patented Sept. 9, 1913.

Application filed December 29, 1910. Serial No. 599,843.

To all whom it may concern:

Be it known that I, SIMON W. WARDWELL, a citizen of the United States, residing at Providence, in the county of Providence and State of Rhode Island, have invented certain new and useful Improvements in Supply-Carriers for Braiding-Machines, of which the following is a specification.

10 My invention relates to braiding machines and particularly to the supply-carriers which support the supply cops or bobbins of yarn or other material.

15 My new device is particularly adapted for use on braiding machines such as that shown and described in my Patent No. 1,032,870, July 16, 1912, in which the yarn supplies are carried in two tiers rotating about a common axis in opposite directions, 20 and I have preferred to illustrate the invention as applied to a supply-carrier of the lower tier.

25 My invention consists of improvements in the structure of the supply-holder and its supporting bracket and in the arrangement of certain other novel details of construction as hereinafter pointed out.

30 The object of my improvement is to provide a means for holding the spindle on which the supply-holder rotates in such manner that it can be easily attached to or detached from the bracket in assembling the mechanism or disassembling it for adjustment and repairs.

35 A further object is to combine the holding means for the spindle with certain elements of the tension-device used in connection with the supply-holder, thereby greatly simplifying the mechanism and reducing 40 the number of parts.

The invention is fully described in the following specification, illustrated by the accompanying drawings, in which:—

Figure 1 is an elevation of the device 45 showing the supply-holder mounted on its bracket which is adapted to be attached to the rotating turret of the braiding machine; Fig. 2, a view of the bottom of the bracket showing the means for fastening the supply-holder spindle in place and illustrating the manner in which said means co-operates with the tension devices; Fig. 3, a sectional view taken through the bracket on the line A—A, looking in the direction 55 indicated by the arrow a.

Referring to Fig. 1 the invention com-

prises the essential elements of a bracket B and cop-holder C, the latter rotatively mounted on the bracket. The bracket B is formed with a foot b adapted to be attached to the machine frame or turret and extends in the overhanging web portion b', strengthened by a rib b², and having one of its sides formed with the curved edge b³, see Fig. 2. Located at approximately the center of the overhanging portion of the bracket is a hub or boss b⁴ formed by enlarging the rib b² at this point, see Fig. 3. The boss b⁴ is bored to receive a spindle D which is secured in position as hereinafter more particularly described, and extends upward from the bracket to serve as a bearing for the rotatable cop-holder C. The cop-holder C is held on the spindle D between the hub b⁴ and a wire ring or washer d sprung into a groove at the top of the spindle.

Referring to Fig. 1, the cop-holder C consists of a stem c formed at the bottom with blades or spurs c' adapted to engage the interior of the cop-tube x, illustrated by dash lines, to secure the cop X rotatively on the holder. Extending upward from the stem c is a spring latch c² having an abutment c³ at its end adapted to extend over the end of the cop-tube to hold the cop from longitudinal displacement. The base of the cop-holder C consists of a wheel or disk F having a down-turned rim f on the interior of which are formed notches or teeth f', see Fig. 2. Mounted on the under side of the bracket B is a pawl or detent G, having its end formed with a toe g adapted to engage the teeth on the rim of the base F. The opposite end of the pawl is pivoted in a hole in the bracket B and its main portion extends through a slot b⁵ in the lug b⁶ to retain it in place. A coiled spring h, held in a pocket b⁷ in the lug b⁶, bears on the side of the pawl to maintain its toe g normally in engagement with the teeth f'. The pawl G is controlled in position in relation to the teeth, to permit or prevent the rotation of the cop-holder, by the varying tension on the yarn which acts through instrumentalities now described.

Extending upward from the outer end of the bracket B is a standard b⁸ provided with bearings for a rock-shaft K which is formed at its upper end with a tension arm k extending at right-angles thereto and provided with a pigtail or thread-guide k' at its outer end. The shaft K is shown as con-

structed of wire and at its lower end is bent to form the horizontally disposed lever k^2 , one arm k^3 of which is adapted to engage the pawl G to release the latter from engagement with the teeth on the base of the supply-holder. The opposite arm k^4 of the lever k^2 is arranged to engage the end of a sliding rod J which cooperates with the stopping devices of the machine, but this mechanism not being essential to the present invention will not be further described. The rock-shaft K is controlled by a spring M connected to the arm k^4 to normally hold the latter against the stop pin n driven into the bracket B . The other end of the spring M is fastened to a lever L pivoted on the pin l which is riveted through the bracket B , as shown in Fig. 3. The lever L is preferably formed of sheet metal and its outer end is bent back in a loop l' adapted to overlap the curved edge b^3 of the bracket B . Formed adjacent the edge b^3 is a series of notches or teeth b^9 disposed radially in relation to the axis of the lever L . The upper portion of the loop l' is formed with an edge l^2 adapted to normally engage with one of the teeth b^9 . It will be seen that by moving the lever L along the quadrant formed by the toothed edge b^3 the operative length of the spring M can be varied to adjust its tension and regulate its effect upon the lever k^2 . It will also be understood that the engagement of the end of the lever with one of the teeth b^9 will retain the lever in its adjusted position against the action of the spring M . The inherent spring tendency of the lever L normally maintains its end in engagement with the teeth or notches on the edge of the bracket and to release it it is only necessary to bend it up to raise its edge l^2 above the top of the teeth.

As illustrated in Fig. 2 the lever L is shaped with an enlarged portion l^4 near its pivot pin, and located at this point is an arcuate slot l^5 formed concentric with the axis of the lever. The lower end of the spindle D is provided with a peripheral groove d' which engages the slot l^5 to retain the spindle in position in the hub b^4 , see Figs. 2 and 3. The slot l^5 is of sufficient length to allow the lever L to be moved the whole length of the quadrant on the edge b^3 of the bracket B without disengaging it from the spindle. When, however, the lever L is moved in the direction indicated by the arrow z beyond the last tooth in the quadrant bracket the spindle D is first pushed down easily removed from the bracket B . In practice the device operates as follows:

To assemble the cop-holder with the bracket the spindle D is first pushed down through the stem c and its lower end inserted in the bore of the boss b^4 . The lever L is next moved in the direction indicated by the arrow z , until its slotted portion lies be-

yond the hole in the hub b^4 and the spindle D can then be pushed clear through the hub to bring its groove d' in line with the edge of the lever. When the lever L is released the spring M will carry it back to engage its slot l^5 with the groove d' in the spindle D and this engagement holds the spindle in its bearing in the hub b^4 and prevents longitudinal movement in either direction. As before stated the slot l^5 is of sufficient dimension to allow the lever L to be moved the whole length of the toothed quadrant on the edge of the bracket B and therefore the lever can be set at different points to adjust the tension of the spring M . The spring M acts to regulate the movement of the rock-shaft K which is operated by the tension of the yarn drawing through the thread-guide k' at the end of the arm k . Where a heavy yarn is being delivered from the supply-holder to the braiding devices of the machine a relatively strong tension is required on the spring M , but for light yarns the tension is reduced to prevent straining or breaking the material. The tension of draft on the yarn y as it is taken up by the braiding operation swings the arm k in the direction indicated by the arrow v and this movement is communicated through the rock-shaft K to carry the arm k^3 of the lever k^2 against the pawl G . A continued pull on the yarn y will act to release the pawl from the teeth of the ratchet on the base of the cop-holder and the latter is allowed to rotate to deliver the yarn in lengths as required. When the draft on the yarn is relieved the arm k will swing back under the influence of the spring M and the pawl G will again engage the teeth f' to prevent further rotation of the cop-holder. In this way a too free delivery or overrunning of the supply-cop is prevented and a proper tension maintained on the yarn as required for the particular style and quality of fabric being braided.

When it is necessary to remove the cop-holder from the bracket to adjust or repair the parts, or for any other purpose, the spindle D can be released from its fastening in the hub b^4 by simply throwing the lever L out of engagement with the groove d' at its lower end. It will be seen that my invention provides a simple, inexpensive and efficient means for securing the spindle D in place in the bracket B and, in addition, the fastening device is arranged to serve a double purpose, acting as it does to effect the adjustment of the tension of the spring M which controls the arm k . In this way I greatly simplify the structure and arrangement of the whole supply-carrier and lessen the number of its parts, while providing for cheaper cost of manufacture and greater efficiency and durability of the mechanism. It will be obvious that various modifica-

tions might be made in form and arrangement of the parts without departing from the spirit and scope of the invention,

Therefore without limiting myself to the exact construction shown, what I claim is:—

1. In a supply-carrier for braiding machines, the combination with a bracket, of a spindle mounted in the bracket, said spindle formed with a peripheral groove, and means pivoted on the bracket to swing in a plane at right-angles to the axis of the spindle and to cross said axis to engage said groove to detachably secure the spindle in place. 70
- 10 2. In a supply-carrier for braiding machines, the combination with a bracket, of a spindle extending through the bracket, and means pivoted on the bracket to swing in a plane at right-angles to the axis of the 75 spindle and to cross said axis to engage the spindle to secure it in position. 80
- 15 3. In a supply-carrier for braiding machines, the combination with a bracket, of a spindle mounted in said bracket, means 85 pivoted on the bracket to swing in a plane at right-angles to the axis of the spindle to engage the latter on opposite sides to secure it in position, and a spring to normally hold said means in engagement with the 90 spindle. 95
- 30 4. In a supply-carrier for braiding machines, the combination with a bracket, of a spindle extending through said bracket, a lever pivoted on the bracket to swing in a plane at right-angles to the axis of the 95 spindle and formed with a slot to engage the spindle on opposite sides, and means to normally hold said lever in engagement with the spindle to secure the latter in position on the bracket. 100
- 35 5. In a supply-carrier for braiding machines, the combination with a bracket formed with a hub, of a spindle extending through said hub and formed with a peripheral groove, and a lever pivoted on the bracket and having a slot adapted to engage said groove in the spindle to secure the latter against longitudinal displacement. 105
- 40 6. In a supply-carrier for braiding machines, the combination with a bracket and a rotatable cop-holder mounted thereon, of a spindle for the cop-holder, and means to secure said spindle in the bracket comprising an adjustable lever pivoted to swing in a plane at right-angles to the axis of the spindle, said lever formed to straddle the latter to engage a groove in one end of the spindle. 110
- 45 7. In a supply-carrier for braiding machines, the combination with a bracket, of a spindle mounted in said bracket, a cop-holder mounted to rotate on said spindle, tension controlled means to regulate the rotation of said cop-holder, a spring to control said means, and a lever connected to 115
- 50 said spring and adjustable on the bracket to regulate the tension of the spring, said lever normally being in engagement with the spindle to secure the latter in the bracket, but movable against the action of the spring to release the spindle. 120
- 55 8. In a supply-carrier for braiding machines, the combination with a bracket, of a spindle extending through said bracket and formed with a groove, a cop-holder rotatably mounted on said spindle, a detent to control the rotation of the cop-holder, a lever operated by the tension on the yarn to release the detent, a spring connected to said lever, and a second lever adjustable on the bracket to regulate the tension of the spring and arranged to normally engage the groove in the spindle to secure the latter in position in the bracket while allowing it to be removed. 125
- 60 9. In a supply-carrier for braiding machines, the combination with a bracket, of a spindle extending through said bracket and formed with a groove, a cop-holder rotatably mounted on said spindle, means operated by the tension on the yarn to control the rotation of the cop-holder, a spring to regulate the action of said means, and a lever connected with said spring and adjustable in position to vary its tension, said lever adapted to engage the groove in the spindle throughout its adjusting movement to hold the latter in the bracket but movable beyond the range of adjustment to release said spindle. 130
- 65 10. In a supply-carrier for braiding machines, the combination with a bracket, of a spindle mounted in said bracket, a cop-holder rotatable on said spindle, means to control the rotation of said cop-holder, a spring to regulate the action of said means, a lever adjustable on the bracket and connected to said spring, said lever adapted to engage the spindle to secure it in position, and means to hold the lever in its adjusted position against the action of the spring. 135
- 70 11. In a supply-carrier for braiding machines, the combination with a bracket or standard, of a spindle mounted in said bracket and formed with a groove, a lever pivoted on said bracket and having an arcuate slot adapted to engage the groove during the turning of the lever on its pivot, a cop-holder rotatably mounted on the spindle, means to control the rotation of the cop-holder, and a spring to regulate the action of said means said spring secured at one end to the lever and tending to normally hold the latter in engagement with the spindle. 140
- 75 12. In a supply-carrier for braiding machines, the combination with a bracket formed with a quadrant having ratchet teeth, of a spindle mounted in said bracket and formed with a groove, a cop-holder rotatable on said spindle, means to control 145

the rotation of the cop-holder, a spring to regulate the action of said means, and a lever pivoted on said bracket and having one end adapted to engage the teeth of the quadrant, said lever connected to the spring and arranged to engage the groove in the spindle during its movement on the quadrant.

13. In a supply-carrier for braiding machines, the combination with a bracket B formed with a quadrant having ratchet teeth, of a lever L pivoted on the bracket with one end adapted to engage said teeth, and a spindle mounted in said bracket and formed with a groove adapted to be engaged by the lever to secure the spindle in position while allowing the adjustment of the lever along the quadrant.
14. In a supply-carrier for braiding

machines, the combination with a bracket B formed with a curved edge having ratchet teeth on one side thereof, a lever L of spring metal pivoted on the bracket with its end adapted to overlap the edge of the bracket to engage the teeth and formed with an arcuate slot, and a spindle mounted in the bracket and formed with a groove adapted to be engaged with the slot in the lever L to secure the spindle in position while allowing the lever to be turned on its pivot.

In testimony whereof I affix my signature 30 in presence of two witnesses.
